UNITED STATES PATENT OFFICE

134,822

DESIGN FOR A SHOE OR SIMILAR ARTICLE

Samuel Zide, Lynn, Mass.

Application October 31, 1942, Serial No. 108,654

Term of patent 3½ years

To all whom it may concern:

Be it known that I, Samuel Zide, a citizen of the United States of America, residing at Lynn, in the county of Essex and Commonwealth of Massachusetts, have invented a new, original, and ornamental Design for a Shoe or Similar Article, of which the following is a specification, reference being had to the accompanying drawing, forming a part thereof.

Fig. 1 is a perspective view of a shoe embodying my new design; and

Fig. 2 is a top plan view thereof.

I claim:

The ornamental design for a shoe or similar article, substantially as shown.

SAMUEL ZIDE,
